Primary Examiner — T Chase Nelson*Assistant Examiner* — Sydney Margaret Parsley(74) *Attorney, Agent, or Firm* — Addison D. Ault;
IPGentleman Intellectual Property Services, LLC(57) **CLAIM**

The ornamental design for a drainage channel, as shown and described.

DESCRIPTION

FIG. 1. is a perspective view of a first and second component of a drainage channel showing the design;

FIG. 2. is a second perspective view thereof;

FIG. 3. is a front elevation view thereof;

FIG. 4. is a rear elevation view thereof;

FIG. 5 is an enlarged left side elevation view thereof;

FIG. 6 is an enlarged right side elevation view thereof;

FIG. 7. is a top plan view thereof;

FIG. 8. is a bottom plan view thereof;

FIG. 9. is a perspective view of the assembled drainage channel showing the design;

FIG. 10. is a perspective view of a first and second component of a second drainage channel showing the design;

FIG. 11. is a second perspective view thereof;

FIG. 12. is a front elevation view thereof;

FIG. 13. is a rear elevation view thereof;

FIG. 14. is a left side elevation view thereof;

FIG. 15. is a right side elevation view thereof;

FIG. 16. is a top plan view thereof;

FIG. 17. is a bottom plan view thereof; and,

FIG. 18. is a perspective view of the assembled second drainage channel showing the design.
